CHARLES W. MILLERD, OF MONTICELLO, ARKANSAS.

Letters Patent No. 88,059, dated March 23, 1869.

IMPROVED COTTON-PRESS.

The Schedule referred to in these Letters Patent and making part of the same.

To all whom it may concern:

Be it known that I, CHARLES W. MILLERD, of Monticello, in the county of Drew, and State of Arkansas, have invented a new and improved Cotton-Press; and I do hereby declare that the following is a full, clear, and exact description thereof, which will enable others skilled in the art to make and use the same, reference being had to the accompanying drawings, forming part of this specification.

Figure 1 is a sectional elevation of my improved press, the section being taken through the line *y y*, fig. 2.

Figure 2 is a cross-section of the same, through the line *x x*, fig. 1.

Similar letters of reference indicate corresponding parts.

The object of this invention is to provide a simple, effective, and easily-operated press for baling cotton and other analogous matter for which it may be found applicable.

It consists in the application and arrangement of a screw and toggle-beam to the follow-block of a press, as herein set forth.

In the drawings, A is the general frame of an upright press, having a cotton-box and bottom, and follow-block G.

Thus far the press is as ordinarily made, the method of operating being to compress the cotton in the body of the frame, or box, down to a compact mass, of such dimensions that it may, after being roped, be rolled out from the lower part of the press, at the lateral openings left by the removal of the doors.

Hitherto, the mechanism for actuating the follow-block downward consisted of various applications of the wheel-and-axle cord, pulley, screw, or combinations of these, all of which were more or less complex, expensive, or difficult to operate, or keep in repair.

My improvement, however, is simple, cheap, and effective, and consists in the application of a screw, D, somewhat obliquely over the follow-block, by means of a beam, C, affixed, as shown, to the upper part of the frame A.

This beam affords attachment for the journal-plate *d*, which latter affords the outer bearing for the screw. The other bearing is afforded by a plate, *e*, affixed to the frame A, as shown.

The screw is furnished with a crank, *f*, or other suitable means for revolving it as a drum or pulley.

The under side of the beam C is channelled, or grooved, and the shoe *b*, (which is formed with a hollow thread, in which the screw works,) moves to and fro on the screw, as the latter is turned, while the channel serves to guide and steady the shoe, thereby causing the beam C to sustain a portion of the thrust resulting from resistance to the follow-block, acting through the toggle-beam E, which connects the follow-block with the shoe.

The follow-block is provided with a suitable number of rollers, *g*, arranged as shown, for the purpose of preventing the development of too much friction when the toggle-beam acts most obliquely, as it does at the first part of its downward movement, and the last part of its upward movement.

The shoe *b* is preferably of cast-iron, and is formed with a recess, in which the upper end of the toggle-beam rests, and exerts its thrust, the end of the toggle-beam being rounded to work smoothly in the rounded angle of the recess.

The pivot-pin serves only to connect the beam to the shoe, and sustains no strain, except when the follow-block is being raised.

The lower end of the toggle-beam is pivoted in a metal thrust-block *a*, affixed on the follow-block, and which receives the thrust of the toggle-beam, when cotton is being pressed.

It will be seen that at the commencement of the downward movement of the follow-block, the toggle is in its most oblique position, and the purchase obtained on it by the screw is least, but the resistance of the matter under the follow-block is also least, and as the toggle-beam assumes a more vertical position, its effect on the follow-block is increased as the resistance of the matter being pressed is increased.

Having thus described my invention, I claim as new, and desire to secure by Letters Patent—

The combination of the grooved beam C, screw D, shoe *b*, toggle-beam E, and follow-block F, all constructed and operating together, substantially as and for the purpose herein shown and described.

CHARLES W. MILLERD.
